United States Patent

Des. 240,161

Patented June 1, 1976

240,161

MICROFICHE VIEWER

Peter Joseph Hall, Willowdale, Ontario, Canada, assignor
to Microfilm Recording Co. Ltd.

Filed July 31, 1974, Ser. No. 493,408

Term of patent 14 years

Int. Cl. D16—02

U.S. Cl. D16—14

FIG. 1

FIG. 2

FIG. 3

FIG. 4

FIG. 5

FIG. 1 is a front perspective view of a microfiche viewer showing my new design;

FIG. 2 is a rear perspective view thereof;

FIG. 3 is a left side elevational view thereof;

FIG. 4 is a front elevational view thereof, and

FIG. 5 is a bottom plan view thereof.

I claim:

The ornamental design for a microfiche viewer, substantially as shown.
